C. S. Schleier,
Curtain-Cord Tightener,
No 19,226. Patented Jan. 26, 1858.

UNITED STATES PATENT OFFICE.

CHARLES S. SCHLEIER, OF BROOKLYN, NEW YORK, ASSIGNOR TO JOHN H. BONN, OF WEEHAWKEN, NEW JERSEY.

WINDOW-SHADE FIXTURE.

Specification of Letters Patent No. 19,226, dated January 26, 1858.

To all whom it may concern:

Be it known that I, CHARLES S. SCHLEIER, of Brooklyn, in the county of Kings and State of New York, have invented an Improved Article of Manufacture—viz., an Improvement in Window-Shade Fixtures; and I do hereby declare that the following is a full, clear, and exact description of the same, reference being had to the annexed drawings, 10 making a part of this specification, in which—

Figure 1, is a vertical central section of my improvement applied to a window. Fig. 2 is a plan or top view of ditto.

15 Similar letters of reference indicate corresponding parts in the two figures. This invention relates to an improvement in the fixtures of window shades or curtains, the kind which are attached to rollers and 20 are adjusted or raised and lowered by the turning of the same.

The rollers are turned by means of cords which pass over pulleys at one end of the rollers at the upper part of the windows 25 and around pulleys attached to the lower part of the windows. These lower pulleys as a general thing in the ordinary fixtures cannot be so attached to the window that their axes will be in the same plane with 30 the axes of the upper pulleys but the axes of the two pulleys will be at right angles with each other and consequently the cords are out of line, one side with the other or, they may be said to be in a half twisted 35 position. The cords in this state or position do not work well, they are liable to run or work off the pulleys and if stretched sufficiently tight to prevent this considerable friction is created thereby.

40 The object of this invention is to obviate the above objection which object is attained as hereinafter described.

To enable those skilled in the art to fully understand and construct my invention I will proceed to describe it.

45

I attach the lower pulley A around which the cord B of the shade passes, to the upper end of a screw rod C. The pulley A is fitted within a socket or block (a), and this socket or block is so attached to the end of the 50 screw rod C, that it may turn freely around on it, it will therefore be seen that the pulley A is a swivel pulley.

The rod C passes through a nut D which is attached to a plate E. This plate is secured to the lower part and at one side of the window as usual.

55 F is the pulley at one end of the roller G around which pulley the cord B also passes, said roller being at the upper part 60 of the window.

From the above description of parts it will be seen that the pulley A may be turned in any position and consequently its axis will always be in the same plane with that 65 of the pulley F and the two sides of the cord E will be in line with each other or in the same plane. The cord may be tightened at any time by turning down the screw rod C, and said rod and the plate E may be covered by any ornamental shell H.

70 Having thus described my invention, I claim and desire to secure by Letters Patent,

75 As an improved article of manufacture, a window-shade fixture, having the swivel pulley A attached to the screw rod C which is fitted in or passes through the nut D on the plate E substantially as herein shown and described for the purpose set forth.

CHARLES S. SCHLEIER.
